(57) **CLAIM**

The ornamental design for a terminal of video conference, as shown and described.

DESCRIPTION

FIG. 1 is a top, front and right side perspective view of a terminal of video conference showing our new design; FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and, FIG. 10 is a top, front and right side perspective view showing the terminal of video conference with cover of the camera opened.

The broken (dashed) lines show portions of the terminal of video conference that form no part of the claimed design. The dot-dashed broken line in FIGS. 1 and 9 shows the boundary of the enlarged views and forms no part of the claimed design.
